ADJUSTABLE SPUD WRENCH

Gary Lamar Robillard, 60 Hathaway,
St. Clair, Mich. 48079

Filed Aug. 14, 1967, Ser. No. 8,249

Term of patent 14 years

(Cl. D54—16)

FIG. 1 is a side elevational view of an adjustable spud wrench embodying my invention;

FIGS. 2 and 3 are, respectively, top and bottom plan views of said embodiment; and

FIGS. 4 and 5 are opposite end elevational views thereof.

I claim:

The ornamental design for an adjustable spud wrench, as shown and described.
